UNITED STATES PATENT OFFICE.

HARVEY C. MUMMERT, OF BUFFALO, NEW YORK.

INTERNAL-COMBUSTION ENGINE.

1,277,742.

Specification of Letters Patent. Patented Sept. 3, 1918.

Application filed October 29, 1917. Serial No. 198,923.

To all whom it may concern:

Be it known that I, HARVEY C. MUMMERT, a citizen of the United States, residing at Buffalo, in the county of Erie and State of New York, have invented certain new and useful Improvements in Internal-Combustion Engines, of which the following is a specification.

This invention relates to internal combustion engines. While of general adaptability, it is particularly adaptable to vehicular uses, and among such uses particularly adaptable to airplane uses, and such typical embodiment as herein shown.

Among the several objects of this invention are: means for more positive valve control; construction of cylinder, and piston and cylinder cooling means; means for maintaining lubrication and cooling of piston and piston-rod bearings; means for positive lubrication of crank-shaft and piston-rod bearings; and especially radical improvements in form and construction of parts to attain simplicity and interchangeability of standardized parts and more extensive use of standardized parts; and the attainment by the means hereafter shown of exactness of construction and adjustment. Other objects will be evident to those skilled in the art from the following specification and claims and from the annexed drawings in which,—

Figure 1 is a side elevation chiefly in central section.

Fig. 2 is a transverse view in section, the left-hand half on the axis of one of the valves and the right-hand half on the axis of a cylinder.

Fig. 3 is a detail section on *a—a*, Fig. 1. I will first indicate the main parts, and then describe the several improvements. The main casting or body is shown at 1, the cylinders at 2, the pistons at 3, the piston-rods at 4, the crank-shaft at 5, the two pairs 45 of valves for each cylinder at 6 and 7, the crown casting at 8, the crank case casting at 9, the propeller bearing at 10, the propeller shaft at 11, a section of the propeller at 12, and the gears connecting the crank-shaft 50 with the propeller-shaft at 13 and 14.

I will first describe my improved valve control. In engines of this high-speed type (the drawings herewith showing an engine having a speed of 2500 R. P. M.) valves 55 which are merely spring-controlled are inadequate. The valve operation must be im-

mediate, positive; for at such speeds, spring lag is sufficient to defeat operation. Mounted in bearings supported by the main casting and the crown casting is a vertical shaft 15 which is driven by miter-gears 16 and 17, connecting it with the crank-shaft 5. Upon the upper end of this shaft 15 is a miter-gear 18 in mesh with the miter gear 19 on the cam-shaft 20. The cam-shaft 20 is in bearings in the crown casting 8. Upon this shaft 20, to each cylinder, is a double cam 21, adapted to act upon the cam-followers 22 and 23 respectively. These cam-followers 22 and 23 are pivoted to rocker-arms 24 which are pivoted on a longitudinal shaft 25, which is rigidly carried by the crown casing 8. The ends of these rocker-arms 24 have adjustable lugs 26 which are adapted to act upon the upper ends of the stems of the two 75 pairs of valves 6 and 7. Resting over the shaft 25 are leaf-springs 27 the ends of which engage with the stems of the valves 6 and 7 through any desired means, as for example through bars 28 connecting each 80 pair of stems of valves 6 and 7. The strength of these springs is such that their action in closing the valves is strong and immediate, as these springs do not have to move any other load than the valves and their stems. 85 Moreover, these springs being away from the immediate effect of the heat from the exhaust gases and being further protected therefrom by the webbing 8^a, they do not deteriorate from heat action. 90

It will now be seen that the action of the rocker-arms 24 is positive and positively synchronized to the piston action, so that there can be no lag or valve opening at any speed, and this positive means for opening 95 the valves permits the use of springs 27 which render the closing of the valves substantially equally positive and immediate, since their only action is to close the valves and are not encumbered with an other 100 weight.

I will next describe the cylinder and piston construction and the cooling means for the same. Heretofore it has been the practice, in engines of this type, to bore the casting for the cylinder and to have the cylinder supported throughout its length by the casting and to have the water jacket space exterior thereto. With such construction there are necessarily two thicknesses of metal between 105 the cooling medium and the interior of the cylinder and necessarily an interposed joint

between the two thicknesses of metal which acts in a considerable measure to reduce the heat conduction. My improvement consists in supporting the cylinders 2 at their upper peripheries by flanges 29 which rest in flange seats 30 in the main casting (see especially Fig. 2) and held in place by the crown casting, and by annular lug supports 31 integral with the main casting, thus forming the cooling space 32 for the fluid of the cooling system. By this means the cooling fluid contacts the cylinder directly without the intervention of any other metal than the cylinder and without any joint, and consequently the cooling effect is more immediate and direct. And this construction leads to the next improved feature of cooling means.

The pistons are provided with the interior webbing 33 which form air spaces between the piston walls contacting the cylinders and the piston-rod bearings. These areas have openings 34 and 35 into the interior of the pistons; and thus the interposed air area between the piston walls and the bearing portions serves materially to lessen the heat conduction to said bearings. The webbing 33 also acts as a conductor for the heat in the piston crown, carrying it to the parts of the piston walls directly cooled by the medium in the area 32. Furthermore, the bearing of the piston rods in the pistons is tubular and open at both ends, as shown at 36, so that the contained air is in direct contact with the portion of the cylinder walls cooled directly by the cooling medium in the spaces 32. This prevents the heat from destroying the lubrication of the piston and piston-rod bearings, which are the bearings most difficult of lubrication that is proper and continuous, especially in airplane engines which must be capable of long-continued action under most difficult conditions.

Next I will describe my improved means of lubricating and lubricant-cooling of the bearings between the crank-shaft and piston-rods. Situated adjacent the bottom of the crank casing where the contained oil is in the coolest condition is an oil-pump 37 which is driven by the shaft 15. Feed pipes (not shown) head from said pump and discharge directly over the oil rings 38 on the crank-shaft 5. These oil rings have in-turned flanges 38^a and leading from the recesses thus formed are oil ducts 39 which lead directly to the crank-shaft, piston-rod bearings at 40. The oil pumped up and delivered into the rings 38 is centrifugally forced into the ducts 39, so that the bearings are positively and continuously lubricated and cooled.

The next feature of my invention relates to simplification and standardizing of parts and to means for securing exact construction, adjustment in assembling and adjust-

ment, repair and replacing of parts. The crank-shaft is mounted in standard anti-friction bearings 41. The inner one of these bearings fits into an annular seat 42. The other bearings fit into annular rings or bushings 43, which in turn fit into annular lug-seats 44 on the main casting. The inner bearing is held in place by a clamp-plate 45 and the bushing 43 are held by set-screws 46.

Referring now especially to Fig. 3 in connection with the other figures, it will be seen that I provide antifriction bearings for the crank-shaft at desired points between cranks. In order that these bearings may be put to place and adjusted before the crank-shaft is put in place in the main casting, I provide the following means: The internal diameter of the ring casing of the antifriction bearings 41 here used is sufficiently large to permit the casing to be slipped over the bends of the crank. When slipped to place, segments 41^a and 41^b which have external flanges to engage over the edges of the bearings 41 and the internal surfaces of which make a close fit with the crank-shaft and which are drilled and threaded to receive screws 41^c, are slipped into place in break-joint position and are then secured together by the screws 41^c.

Thus the crank-shaft and its bearings may be assembled and adjusted before putting to place in the main casting; and when put in place the bushings are secured and the piston-rods attached and adjusted. This not only simplifies assembling and adjustment of parts, but permits accurate machining of the main casting; for it will be seen that, with this construction, the bearings of the main casting to receive the crank-shaft are all concentric, so that the alignment of parts may be made substantially absolute.

And this same general improvement is applied to the cam-shaft 20. The shaft, its bearings and cams are all adjusted to place and then inserted in a single boring in the crown casting 8, which has annular lugs substantially the same as the lugs above described for the bearings of the crank-shaft. It will be understood, of course, that the gear 19 is put in place and secured to the shaft 20 after the said shaft and its bearings are in place.

These improvements, dispensing largely with former construction methods which required a large part of the assembling and adjusting within the castings, render possible the successful employment of American methods of interchangeable construction and machine manufacture, which eliminate to the last degree hand fitting and the employment of skilled labor.

It will be seen that the shaft 15 drives the pump 47 which maintains the circulation

of the cooling medium, and also drives the magnetos (one being shown in outline at 50) through the gears 48 and 49.

Having thus described my invention, I 5 claim:

1. In an engine of the type described, the combination with inlet and exhaust valves, and a cam-shaft, of a rocker arm acting upon the stems of both of said valves, cams 10 on said cam-shaft bearing against and positively actuating said rocker arm on both movements, and springs for closing said valves.

2. In an engine of the type described, the 15 combination with inlet and exhaust valves, and a cam-shaft, located between the valve stems, of a rocker arm pivoted upon a shaft parallel with and above said cam-shaft and adapted to act upon the stems of both of

said valves, double cams on said cam-shaft 20 bearing against and positively actuating said rocker-arm in both directions, and springs for closing said valves.

3. In an engine of the type described, the combination with inlet and exhaust valves, 25 of a cam-shaft, a crown casting in which said cam-shaft is journaled, a rocker-arm shaft in said crown casting lying above and parallel with said cam-shaft, a rocker-arm on said rocker-arm shaft, double cams on 30 said cam-shaft positively actuating said rocker-arm in both directions of movement, adjustable means on said rocker-arm engaging the stems of said valves, and springs over said rocker-arm shaft having their free 35 ends meditately connected to the stems of said valves to close said valves.

HARVEY C. MUMMERT.
